UNITED STATES PATENT OFFICE.

YVES MARREC, OF LONDON, ENGLAND, ASSIGNOR TO MARREC LIMITED, OF LONDON, ENGLAND.

TELEGRAPHY AND RADIOTELEGRAPHY.

Application filed April 2, 1925, Serial No. 20,069, and in Great Britain April 14, 1924.

This invention relates to ordinary telegraphy along wires and to wireless telegraphy, of the type in which signals of different frequencies are transmitted simultaneously, and has for its object a method of this type in which the signals have several different frequencies which are relatively near to each other.

In the systems of transmission of the type referred to hitherto employed, a relatively large frequency difference between the signals to avoid perturbations caused by resulting beats whose intensity is much greater than the intensity of the individual signals, is employed. This is a drawback, as an aerial or transmission line adapted to a certain frequency does not give so good results with other frequencies. The intermittent nature of the beats was also a greater obstacle than if the beats had been permanent.

According to this invention, applicant produces by any suitable means at the sending end (line, cable or aerial), as many different frequencies as there are signals which it is desired to transmit simultaneously, provided that the said frequencies differ from each other by at least 20 oscillations per second and that none of the beats caused by these simultaneously transmitted oscillations of different frequencies have the same frequency as one of the frequencies separately used for the transmission of different signals, the latter having as much as possible the same intensity.

Applicant also transmits at the sending end during the spacing period supplementary compensating oscillations for each distinct frequency used for signalling, in order to maintain permanently the beats which, although modified in period, are nevertheless not modified enough to disturb the signals as they do when they are intermittent, the oscillations of said spacing frequencies being approximately of the same intensity as the frequencies used for signalling.

In order to modify, not the electrical conditions, which remain constant actually, but only the frequency of the signals, for producing the intervals between the signals, the frequencies of the compensation or spacing oscillations must be very near their signalling frequencies, but they must be at least of the order of 10 ~ above or below the signalling frequency.

The different signalling frequencies can

also be very near, of the order of difference 20 ~, on the condition that beats will be produced by these signalling frequencies, corresponding to one of them. For the reception the receivers corresponding to each different signalling frequency are disposed so as to eliminate the currents to the frequencies of which they are not tuned, for instance by utilizing to this end a selective receiving system as described in applicant's co-pending specification Serial No. 656,450. With such a receiving system, the intermittent objectionable currents are not received, but they have the drawback of cutting the signals if they occur at the same time, this being due to the fact that the desired currents and the objectionable currents neutralize one another and do not produce the trigger effect described in the said co-pending specification Serial No. 656,450. However, if a permanent current of invariable intensity is available, the period of which is only slightly altered while remaining always sufficiently different from the frequency to which the selective circuit is tuned, it is sufficient to adjust the point at which the trigger effect takes place in order to cause this effect to take place not only under the sole action of the current to which the system is tuned, but under the combined action of the permanent beat current and of the currents to which the selective circuit is tuned.

By this process, applicant is enabled to perform, on the same line, in the case of ordinary telegraphy, or on the same aerial, in the case of wireless telegraphy, the multiplex reception after detection, by as many selectors in parallel as there are messages to receive simultaneously each selector operating only under the action of the currents to which it is tuned, in a limit of about 10 ~ above or below its resonance frequency.

If originally arranged so that no beats are produced, and the current then obtained is kept constant irrespective of the frequency, then no beat will be produced if all the frequencies are varied by the same amount.

In the case of radio-telegraphy, for instance, one can utilize any wave length which will function at the same time as a carrier wave for the several modulation waves in multiplex transmission and as a transmission wave on this particular wave length, by changing slightly the wave length

to bridge the intervals between the signals. Besides this ordinary high frequency transmission, for each simultaneous transmission, two modulation waves will be used, corresponding to each separate transmission, one of these modulation waves being a compensation wave, as described above. For instance, with five transmissions superposed to the carrier wave, one may have the following arrangement:—

Transmission.	Frequency of signals.	Frequency of compensations or spaces.
15 No. 1-----	600	620
No. 2-----	700	720
No. 3-----	800	820
No. 4-----	900	920
No. 5-----	2,500	2,520

20 In the case of a line transmission, there is, of course, no carrier wave.

Referring to the drawings filed herewith, which illustrate diagrammatically, as an example, the arrangement for multiplex working just described:—

25 m_1-m_5 are the five modulators; s_1-s_5 are the five selectors; t_1-t_5 are the corresponding transmitters modifying the frequency of the modulators; c_1-c_5 are the capacities 30 which may, or may not be short circuited, in order to alter the transmitted frequency according as to whether the key of the corresponding transmitter is pressed down or not.

35 In the case of line or cable transmission, the line is connected to the terminals a and a' , the terminals b b' being earthed. In the case of wireless transmission, the terminals a b are connected to the modulation circuit 40 of the transmitter; for multiplex reception at one station, the terminals a' b' are connected to the ordinary receiver instead of the telephones.

45 By the arrangement of keys shown, the frequency is varied but the oscillating signal current remains of a constant strength, so that the beats produced between the different signalling frequencies are of less strength and therefore less objectionable 50 than if the oscillating signal currents were of varying strength, as explained above.

The modulators are, for instance, three-electrode valves with inductances in the plate and grid circuits, one inductance being shunted by a condenser in series with the corresponding condenser (C_1-C_5 in the figure) to control the frequency.

In order to increase the number of mes-

sages transmitted simultaneously, use may also be made of inaudible frequencies above 60 the audible frequencies; in this case it will be sufficient to utilize, for receiving them, selectors tuned to these inaudible frequencies, using, if necessary, a local heterodyne 65 for producing beats which will be detected for the production of audible signals.

In order to utilize the process advantageously, it is advisable to use the receivers referred to above so as to use frequencies very close to one another to avoid occupying in the 70 case of wireless telegraphy, a great range of wave lengths which would be objectionable in view of other foreign communications. As a very sharp selection is obtainable with these systems, however, differences of received frequencies of the order of 15~ 75 would be sufficient, this constituting a range not exceeding 50~, which would cause no more perturbations to the foreign communications than if one utilized a single frequency in the present conditions. The signals are selected as explained above, and recombined to constitute the message.

What I claim and desire to secure by Letters Patent is:—

1. A system of telegraphy along lines or of wireless telegraphy, of the type described, in which, for each signal frequency used, a spacing frequency is transmitted for the purpose of sustaining the signaling beats and avoiding the disturbance due to their otherwise intermittent character.

2. A system of line or wireless telegraphy as claimed in claim 1, further characterized in that a compensating wave is transmitted between the signals, the frequency of which compensating wave is very near the frequency of the corresponding signal, but not less than 10~ above or below the latter.

3. A system of line or wireless telegraphy as claimed in claim 1, in which a compensating wave is transmitted between the signals, the frequency of which compensating wave is very near the frequency of the corresponding signal, but not less than 10~ above or below the latter, further characterized in that the different signalling frequencies are very near to each other, but do not differ by less than 20~, provided that none of the signaling beats produced by these frequencies correspond to one of the frequencies itself.

In testimony whereof, I affix my signature.

YVES MARREC.
